Term of patent 7 years

(Cl. D62—4)

FIG. 2

FIG. 3

Figure 1 is a front perspective view of a front panel for a room air conditioner or the like embodying my new design.

Figure 2 is a cross-sectional view taken substantially on line 2-2 of Figure 1 with portions broken away for convenience of illustration.

Figure 3 is a fragmentary cross-sectional view taken substantially on line 3-3 of Figure 1 with portions broken away for convenience of illustration.

The essential feature of the design resides in the portions shown in full lines.

I claim:

The ornamental design for a front panel for a room air

conditioner or the like, substantially as shown and described.
